UNITED STATES PATENT OFFICE

PORTER H. BRACE, OF FOREST HILLS, PENNSYLVANIA, ASSIGNOR TO WESTINGHOUSE ELECTRIC & MANUFACTURING COMPANY, A CORPORATION OF PENNSYLVANIA

INDUCTION-FURNACE COIL

Application filed August 14, 1929. Serial No. 385,765.

My invention relates to electric furnaces and particularly to electric induction furnaces of the surrounded-pool type.

An object of my invention is to provide a relatively simple and highly efficient coil structure for an induction furnace of relatively large size.

Another object of my invention is to provide an induction coil, for a relatively large furnace embodying a crucible, that shall embody inherent means for maintaining itself in close operative engagement with the outside of the crucible.

Another object of my invention is to provide a furnace coil having one or more relatively short portions of greater resiliency than the other portions thereof, in combination with auxiliary resilient means operating to maintain the coil in close operative engagement with the outside of a crucible, irrespective of the expansion and contraction thereof, incident to heating and cooling.

In practicing my invention, I provide a refractory lining or crucible, a casing surrounding the same and spaced therefrom, which casing may be provided with means for permitting of tilting the crucible, and a helically wound coil having a plurality of turns, each turn having major portions extending through a predetermined path peripherally of, and in close operative engagement with, the outside periphery of the crucible, each turn having at least one relatively short portion of greater resiliency than the major portion and bowed or deformed out of the normal path of the turn. I provide also a plurality of resilient supporting or pressing means operatively engaging the relatively short portions of each turn to assist in maintaining the major portions of each turn in close operative engagement with the outside of the crucible.

In the single sheet of drawings,

Figure 1 is a top plan view of an induction furnace embodying my invention.

Fig. 2 is a view, in vertical section, taken on the line II—II of Fig. 1.

Fig. 3 is a fragmentary view of a modified form of the coil structure embodying my invention, and

Fig. 4 is a section, taken on the line IV—IV of Fig. 3.

My invention is particularly applicable to induction furnaces of the surrounded-pool type and of relatively large size, in which it is highly desirable, if not actually necessary, that close operative engagement be maintained between the energizing coil surrounding the crucible and the crucible itself in order that the inter-linkage of the lines of force generated by the current-traversed energizing coil with the material in the crucible shall be a maximum.

A crucible 11 is shown as being built up of suitable bricks or blocks of a refractory material adapted to withstand the high temperatures of the material to be melted in the crucible. While a built-up crucible is shown, this is more particularly for illustrative purposes and I may use a crucible embodying a properly shaped mass of material, such as may be used in the case of smaller crucibles. A casing 12, which may be of metallic or of non-metallic material, is located around the crucible, a filling 13 of sand or other granular heat-insulating, as well as electric-insulating, material being provided. A tubular shroud 14 of electric-insulating material is located around the crucible in order to reduce the amount of granular material necessary to be used. The crucible 11 may rest on a bottom layer of the granular material 13, as is shown more particularly in Fig. 2 of the drawings.

An energizing coil 16 is provided around the crucible and embodies a substantially solid portion 17 for carrying an electric current and a tubular portion 18 for carrying a cooling fluid. As shown in Fig. 2 of the drawings, the tubular portion 18 is separate from, or brazed or otherwise secured to, the solid portion 17.

The solid portion 17 is made in arcuate sections, shown as being four in number in Fig. 1 of the drawings, connections between the adjacent ends of the sections of the conductor 17 being effected by resilient bowed strips 19 the ends of which are suitably interfitting with the ends of the sections of the conductor 17 and brazed therein or other-

wise secured thereto. The tubular member 18 is provided with a bowed-out or deformed portion 21, which, in the case of the construction shown more particularly in Figs. 1 and 2 of the drawings, extends radially outward from the crucible or radially relative to the axis of the crucible and of the coil.

Auxiliary resilient supporting and clamping means are provided and include a vertically extending bar 22 having a plurality of laterally extending integral lugs 23 thereon, springs 24 being fitted over the respective lugs 23, one end of each spring engaging the rod or bar 22 and the other end engaging a lug 26 integral with the casing 12. The lugs 23 and the springs 24 extend tangentially of the coil 16 and assist the inherent resiliency of the portions 19 and 21 of the coil to maintain the conductor in close operative engagement with the crucible and more particularly with the member 14.

Figs. 3 and 4 show a modification in which a coil, having a plurality of turns of a conductor 31, including a solid current-conducting portion and a tubular cooling fluid-conducting portion, has integral relatively short portions 32 bent out of the normal path of the major portion of the turn, in this case, downwardly from the plane of the turn. While I have shown no auxiliary resilient clamping or pressing portions, such as are shown in Fig. 1 of the drawings, it is to be understood that I may use these if necessary.

The casing 12 may be provided with short shafts or trunnions 33 to permit of tiltably supporting the entire furnace structure in order to effect removal of the molten material through a pouring spout 34.

No electrical connection from a supply circuit to the coil 16 is shown, as any suitable or desired construction of such parts may be provided, in a manner well known in the art.

When an induction furnace of relatively large size is employed, it is highly desirable, if not necessary, that the inner diameter of the energizing coil be but little larger than the outside of the crucible in order to reduce the amount of leakage flux, and hence, the radial thickness of the material 13 is made as small as possible, as is also the radial thickness of the member 14. As the crucible will expand and contract, incident to its heating and cooling, in actual use, the device embodying my invention provides a means for maintaining the inner face of each turn of the conductor in close operative engagement with the crucible or with material immediately surrounding the crucible, so that the coil will follow the expansions and contractions of the crucible, when in use, thereby tending to prevent the development

of fissures and consequent leakage of molten metal.

The device embodying my invention provides one or more relatively short portions of a conductor which extend through a circuitous path aside from the normal path of the turn or, in other words, a minor portion of each turn is deformed or bowed laterally of the turn. This provides a short portion of greater resiliency than the other portion of each turn and, in cooperation with auxiliary resilient pressing or clamping means engaging the minor portions, effects following-up of the movements of the crucible by the coil during operation of the furnace.

Various modifications may be made in the device embodying my invention without departing from the spirit and scope thereof, and I desire, therefore, that only such limitations shall be placed thereon as are imposed by the prior art or are set forth in the appended claims.

I claim as my invention:

1. In an electric heating device for inductively heating a mass of material, an energizing coil, a shroud of electric-insulating material operatively engaged by the coil, each turn of the coil having at least one relatively short portion deformed from the normal path of the turn, whereby each turn of the coil may follow the expansion and contraction of the shroud as it is heated or cooled while remaining in operative engagement therewith.

2. In an electric heating device for inductively heating a mass of material, an energizing coil surrounding said mass of material, each turn lying in a path conforming substantially to the periphery of the mass of material, the coil including a solid current-conducting portion and a tubular cooling-fluid-conducting portion, each turn of the coil including at least one relatively short portion bent laterally out of the plane of the normal path of the turn.

3. In an electric heating device for inductively heating a mass of material, an energizing coil surrounding the mass of material in operative engagement therewith, each turn of the coil including a portion of greater resiliency than the other portions and extending through a circuitous path aside from the normal path of the turn.

4. In an electric heating device for inductively heating a mass of material, an energizing coil surrounding the mass of material in operative engagement therewith, each turn of the coil including a portion of greater resiliency than the other portions and extending through a circuitous path aside from the normal path of the turn and resilient means operatively engaging the turn to maintain it in operative engagement with the mass of material as it expands and contracts incident to heating and cooling.

5. In an electric heating device for inductively heating a mass of material, an energizing coil closely surrounding the mass of material to be heated and in operative engagement therewith, each turn of the coil including a plurality of relatively short portions of greater resiliency than the major portion of the turn and bowed out of the normal path of the turn, and resilient means at each side 10 of the short portions for holding the major portion of the turn in operative engagement with the mass of material during expansion and contraction thereof.

6. In an electric heating device for inductively heating a mass of material, an energizing coil surrounding the mass of material and resilient means acting substantially tangentially on the coil to maintain it in close operative engagement with the mass of material as said mass expands and contracts incident to heating and cooling.

7. In an electric heating device for inductively heating a mass of material, an energizing coil surrounding the mass of material 25 and closely engaging the same, each turn of the coil including at least one relatively short portion bowed out of the normal path of the turn, and resilient means acting substantially tangentially on the ends of the bowed portions to maintain the major portions of each 30 turn in close operative engagement with the mass, irrespective of its expansion and contraction.

In testimony whereof, I have hereunto 35 scribed my name this 30th day of July, 1929.
PORTER H. BRACE.
